UNITED STATES PATENT OFFICE.

GEORGE LESLEY WACKEROW, OF MILWAUKEE, WISCONSIN, ASSIGNOR
OF ONE-HALF TO CARL RUNGE, OF MILWAUKEE, WISCONSIN.

CORN-HUSKING MACHINE.

SPECIFICATION forming part of Letters Patent No. 761,562, dated May 31, 1904.

Application filed January 24, 1903. Serial No. 140,366. (No model.)

To all whom it may concern:

Be it known that I, GEORGE LESLEY WACKEROW, a citizen of the United States, residing at Milwaukee, county of Milwaukee, and State 5 of Wisconsin, have invented new and useful Improvements in Corn-Husking Machines, of which the following is a specification.

My invention relates to improvements in corn-husking machines, and pertains especially to that class of such machines in which the ears are stripped from the standing stalks and husked during the progress of the machine. So far as I am aware, the machines of this class as heretofore constructed have 15 been provided with snapping-rollers which were located in the stalk-passage, and various expedients have been devised in such machines to direct the ears to the husking-rollers; but as the ear-directing devices must 20 also be operative in the path of the stalks and in front of the snapping-rollers considerable difficulty has been experienced in properly directing the ears without interfering with the stalks.

25 The object of this invention is to provide a form of construction in which the snapping-rollers are located at one side of the stalk-passage and the stalks bent laterally to the line of such rollers and passed between them 30 for the separation of the ears, the stalks being then permitted to swing backwardly into position as the machine moves forwardly.

In the following description reference is had to the accompanying drawings, in which—

35 Figure 1 is a plan view of my invention. Fig. 2 is a detail view of the snapping-roller driving connections. Fig. 3 is a detail side view of the stalk-feeding chains in their relation to each other. Fig. 4 is a front elevation.

Like parts are identified by the same reference characters throughout the several views.

A main frame 1 and an auxiliary frame 2 are connected together by arches 3, leaving a 45 stalk-passage underneath the arches. The frames are supported upon a traction drive-wheel 5 and a grain-wheel 6, with which they are respectively connected, the wheel 5 being

fast on a main driving-shaft 7, suitably journaled in frame 1.

50 9 and 10 are the snapping-rollers. These are journaled in the main frame, with a downward, forward, and lateral incline and with their lower ends adjacent to the stalk-passage formed by arches 3. The main frame is provided with a forwardly-extending inclined tapered platform 15. The auxiliary frame is also formed with a forwardly and laterally extending guide 16, the frame 15 and guide 16 operating like a broad open fork to gather the 55 fallen stalks into the stalk-passage.

A gathering-chain 18 revolves in a substantially horizontal plane along one side of the stalk-passage and is provided with fingers 19, which project into the passage and travel 65 rearwardly therein. These fingers engage and push the stalks rearwardly toward the snapping-rollers. A yielding bar 20, projecting rearwardly from the auxiliary frame and bearing upon a resistance-spring 21, is 70 used to insure the engagement of the stalks by the fingers. A series of slats 23 are also secured to the auxiliary frame and project from their point of attachment backwardly, upwardly, and across the stalk-passage into 75 proximity to the upper snapping-roller, the lower slat 23 projecting into proximity with the lower end of such roller and the others being of progressively-increasing length and curved, so that the series of slats taken together occupy a curved plane of somewhat 80 similar form to that of the moldboard of a plow. The function of these slats is to bend the stalks laterally and cause them to pass between the snapping-rollers. Revolving feeding-chains 26 and 27 are provided with feeding-fingers 28 and arranged to coöperate with the slats 23 in directing the stalks between the snapping-rollers. The lower ends of 85 these rollers are tapered, as shown, and the chain 26 extends between the tapered ends of the rollers above the feeding-chain 18 and revolves in a vertical plane. The chain 27 also revolves in a vertical plane, but has an upward pitch from near the lower front portion of the main frame to a point in front

90 95

of the lower snapping-roller. The feeding-fingers of these chains engage the stalks which are bent over by the slats 23 and carry them to a position where they are caught between 5 the snapping-rollers. The detached ears drop upon a conveyer-apron 30, whereby they are delivered to husking-rollers 31, of ordinary construction. From the husking-rollers the ears are delivered to a conveyer 32, which 10 elevates them to a point of final discharge into the box of a wagon traveling adjacent to the husker. The stalks after having passed between the snapping-rollers are permitted to straighten and are left standing as the machine moves forwardly. 15

Motion is transmitted from the main driving-shaft 7 to the lower snapping-roller through the beveled gear-wheels 35 and 36, tumbling-rod 37, and beveled gear-wheels 38 and 39. The upper snapping-roller is driven from the lower one by spur gear-wheels 40 and 41. The gathering-chain 18 runs over end sprocket-wheels 42 and 43 and is driven from the main shaft by a sprocket-chain 44, 20 shaft 45, beveled gear-wheels 46 and 47, and vertical shaft 48. The sprocket-pinion 49 of the feeding-chain 26 is mounted on the shaft 45 and motion transmitted to the feeding-chain 27 through the chain 26, its front sprocket-wheel 50, shaft 51, and sprocket-wheel 52 thereon. The upper or rear end of the chain 27 runs over an idle sprocket 53 adjacent to the lower snapping-roller. The husking-rollers are driven from the main shaft by beveled 25 gear-wheels 55 and 56, shaft 54, sprocket-chain 58, and the interacting spur gear-wheels 57 of these rollers. The apron 30 is mounted on rollers 59 and 60 and the roller 59 driven from the husking-rollers by a sprocket-chain 61. 30 The conveyer 32 is driven from the shaft 54 by a sprocket-chain 65, which drives the lower conveyer-shaft 66.

While I have illustrated the motion-transmitting connections above described, it will be 45 understood that any suitable mechanism for driving the working parts of the machine may be employed.

In operation the machine is driven along the rows of corn with the arches straddling 50 the hills. The gathering chains and fingers run backwardly at a somewhat greater speed than the forward movement of the machine and carry the stalks against the curved slats, which bend them over into the path of the 55 snapping-rollers, which are arranged one above the other in position to receive the stalks. The fingers of the feeding-chains 26 and 27 catch the bent stalks and coöperate with the slats in directing them between the 60 snapping-rollers. The remaining operations of the machine are obvious from the illustration. The ear-conveying apron covers a broad space and is adapted to receive all ears and convey them to the huskers, and the operation

of the husking-rollers and ear-conveyer is 65 well known in the art.

Having thus described my invention, what I claim as new, and desire to secure by Letters Patent, is—

1. In a machine of the class described, the 70 combination of a wheeled vehicle provided with a stalk-passage, a set of snapping-rollers located at one side of the stalk-passage, and inclined downwardly, and forwardly and toward the passage; means for driving the snapping-rollers; and means for deflecting the upper portions of stalks in the stalk-passage into the path of the snapping-rollers. 75

2. In a machine of the described class, the 80 combination of a wheeled vehicle having a stalk-passage between the wheels and a raised connection between the parts of the vehicle on opposite sides of the passage; a set of snapping-rollers, having a downward and forward 85 inclination toward said passage; means for driving the snapping-rollers; a gathering-chain having fingers operative in the stalk-passage to press the stalks rearwardly and stalk-bending devices adapted to direct the upper portion of the stalks between the snapping-rollers. 90

3. In a machine of the described class the 95 combination of a wheeled vehicle having a stalk-passage between the wheels and a raised connection between the parts of the vehicle on opposite sides of the passage; a set of snapping-rollers, having a downward forward and lateral inclination toward said passage; means for driving the snapping-rollers; a gathering-chain having fingers operative in the stalk-passage to press the stalks rearwardly and stalk-bending devices adapted to direct the upper portions of the stalks between the snapping-rollers; together with a set of husking-rollers and a conveyer-apron operative underneath the snapping-rollers to convey detached ears to said husking-rollers. 100

4. In a machine of the described class the 110 combination of a wheeled vehicle having a stalk-passage between the wheels and a raised connection between the parts of the vehicle on opposite sides of the passage; a set of snapping-rollers, having a downward and forward 115 inclination and a lateral inclination toward said passage; means for driving the snapping-rollers; a gathering-chain having fingers operative in the stalk-passage to press the stalks rearwardly and stalk-bending devices adapted to direct the upper portions of the stalks between the snapping-rollers; together with a yielding bar arranged to bear resiliently upon the stalks in the stalk-passage in the direction of the gathering-chain, whereby the engagement of the stalks by said chain is insured. 120

5. In a machine of the described class, the 125 combination of a portable vehicle; a set of snapping-rollers mounted on the vehicle one above the other and having a downward for-

ward and lateral inclination; means for driving the rollers; and devices for bending standing stalks into position for engagement between said rollers; together with a set of husking-rollers, and a conveyer-apron operative underneath the snapping-rollers, to deliver detached ears to the husking-rollers.

6. In a machine of the described class, the combination of a portable vehicle provided with a stalk - passage; curved stalk - bending slats extending across the passage, and means for detaching the ears from the bent stalks.

7. In a machine of the described class, the combination of a portable vehicle provided with a stalk-passage; a stalk-bending device extending angularly across the passage; and means for detaching ears from the bent stalks.

8. In a vehicle of the described class, the combination of a portable vehicle provided with a stalk-passage; a stalk-bending device extending angularly across the passage; and means for detaching ears from the bent stalks; together with a set of husking-rollers, and a conveyer operative underneath the ear-detaching mechanism to deliver the ears to the husking-rollers.

9. In a machine of the described class, the

combination of a portable vehicle provided with a stalk-passage; gathering devices operative to gather standing and partially-fallen stalks into said passage; a conveyer for detached ears, located at one side of the passage; means for deflecting the upper portions of the stalks over the conveyer and means for detaching the ears from the stalks while over the conveyer.

10. In a machine of the described class, the combination of a portable vehicle provided with a stalk-passage; a set of snapping-rollers located at one side of said passage; stalk-bending devices extending from the other side of the passage in the direction of the snapping-rollers and adapted to direct stalks of corn to the snapping-rollers; said snapping-rollers being arranged to deliver the ears upon a portion of the vehicle at one side of said stalk-passage.

In testimony whereof I affix my signature in the presence of two witnesses.
